UNITED STATES PATENT OFFICE.

CHARLES B. THWING, OF PHILADELPHIA, PENNSYLVANIA, ASSIGNOR TO THWING INSTRUMENT COMPANY, OF PHILADELPHIA, PENNSYLVANIA, A CORPORATION OF PENNSYLVANIA.

RADIATION-PYROMETER.

1,232,408.

Specification of Letters Patent.

Patented July 3, 1917.

Application filed May 4, 1914. Serial No. 836,341.

To all whom it may concern:

Be it known that I, CHARLES B. THWING, a citizen of the United States, residing in Philadelphia, Pennsylvania, have invented 5 certain Improvements in Radiation-Pyrometers, of which the following is a specification.

One object of my invention is to provide a form of radiation pyrometer which, by 10 reason of its construction and arrangement of parts, shall be relatively inexpensive to manufacture and durable under operating conditions, the invention contemplating a relatively simple construction which, while 15 giving accurate results, can be made of comparatively cheap materials.

These objects and other advantageous ends I attain as hereinafter set forth, reference being had to the accompanying drawings, in which Figure 1 is a section illustrating a radiation pyrometer constructed according to my invention, and Fig. 2 is a fragmentary section illustrating a modification of my invention.

25 In the above drawings, 1 represents a portion of the wall or arch of a furnace, or of a brick or other kiln, having an opening in which is mounted a muffle 2. This latter preferably has the form of a hollow refractory cylinder flanged at one end and closed at its opposite end, its length being such that said closed end projects into the kiln, furnace, etc., for some distance beyond the inner face of the wall 1.

35 A suitable number of refractory blocks 3, 3^a and 3^b should be mounted outside of the muffle whose outer end as well as said blocks I inclose in a suitable metallic protective casing 5. Each of the blocks above mentioned is perforated and through them extend the elements 6 and 7 of the pyrometer or whatever other temperature responsive device is employed, this being shown in the present instance as inclosed within a thin 40 refractory tube 8 supported by the blocks 3, 3^a and 3^b and closed at its inner end, which terminates in the muffle outside the plane of the inner face of the wall 1.

The thermo elements 6 and 7, or whatever 50 other device is designed to be acted on by the heat of the kiln in order to give an indication of the temperature of the same, likewise terminate within the muffle between the planes of the inner and outer faces of 55 the wall 1, and it will be noted that the tube

8, although preferably employed for the protection of this part of the instrument, may be omitted if found advisable without departing from my invention.

A fourth block 9, preferably fixed to a 60 metallic cap 10, is designed to fit over the outer open end of the protective tube 8 and the thermo elements, so as to maintain the temperature of their cold ends substantially constant, being provided with a handle 11 65 whereby it may be conveniently manipulated.

While the inner end of the muffle 2 should properly project into the furnace or kiln beyond the inner face of the wall 1, it is, of course, possible that it might be flush with the inner face of the wall or might even be terminated below the same, as shown at 2^a in Fig. 2, but such constructions do not give as satisfactory results as that illustrated. 75

With a muffle whose closed inner end projects a definite distance within or beyond the inner surface of the kiln wall 1 it will be understood that said end is exposed to the kiln heat which, being radiated from its inner surface, affects the thermo elements 6-7 80 in the well known manner to an amount which is a function of the temperature of the kiln. Owing to the fact that the temperature to which the thermo elements are 85 exposed is, therefore, considerably lower than that of the kiln or furnace, it is permissible to make them of inexpensive and yet durable materials.

Since the convection currents within the 90 muffle are relatively slight and since the amount of heat radiated from the muffle walls immediately adjacent the inner ends of the thermo elements 6-7, or other temperature responsive device, is also practically negligible, it is obvious that said device is affected by and raised to a temperature which is practically dependent upon the amount of heat radiated from the heated inner end of the muffle 2, and hence directly 100 related to the temperature of the kiln. In order, therefore, to obtain correct and accurate readings of the temperature of the kiln it is only necessary to properly calibrate the indicating or recording instrument connected to the temperature affected member or thermo elements within the muffle. 105

It is, of course, immaterial whether the apparatus connected to the instrument 6-7 be merely a device for visually indicating 110

variations of temperature or whether it be one which will make records either continuously or at definite intervals. In any case, those parts of the apparatus which are exposed to the heat from the kiln are of a simple and relatively substantial construction which may be inexpensively installed and maintained.

While I have shown the muffle as having its inner end closed, it is obvious that without departing from my invention said end may in some cases be open as indicated in Fig. 2, in which case, the radiations from the interior of the kiln would affect the thermo-element directly instead of through the end of the muffle, said couple in any case being spaced away from the walls of said muffle. It is, therefore, to be noted that the thermo element is mounted within a muffle so as to be some distance from its adjacent walls and that said muffle is placed in the wall of the kiln or furnace in such position that the thermo elements lie to the rear of the plane of the inner surface of said wall.

25 I claim:

1. The combination in a radiation pyrometer of a hollow refractory structure forming a muffle; a refractory block mounted on the muffle; a pair of elements constituting a thermo-couple mounted in the block with its hot end extending part way into said muffle so as to lie within a relatively cool portion thereof in position to receive heat radiated from a materially hotter portion.
- 35 2. The combination in a radiation pyrometer of a hollow refractory structure forming a muffle; a refractory block mounted on the muffle; a pair of elements constituting a thermo-couple mounted in the block with its hot end extending into the muffle in position to be acted on by heat radiated from the inner walls thereof; with a cap
- 40 for inclosing and maintaining substantially

constant the temperature of the cold end of the thermo-couple.

3. The combination of a refractory wall exposed to heat; a muffle mounted in said wall with its inner end projecting beyond the inner face thereof; and a thermo-couple mounted to extend in the outer part only of said muffle in position to be acted on by heat radiated from the inner surface of that part thereof which projects inside the walls.

4. The combination of a refractory wall exposed to a source of heat; a muffle extending through said wall and having a closed end projecting beyond the inner face thereof; with a thermo-couple extending into said muffle but terminating outside the plane of the inner face of the wall in position to be affected by heat radiated from the inner surface of the closed end of the muffle.

5. The combination of a muffle in the form of an elongated hollow structure of refractory material closed at one end; a casing mounted at the opposite end of said muffle; a thermo-couple mounted in the casing and projecting part way only into the hollow of said muffle; with a removable cap for the casing inclosing the opposite end of said instrument.

6. The combination of a source of heat having a refractory wall; a muffle in said wall; and a pyrometer in the muffle spaced away from the adjacent walls thereof and on the outer side of the plane of the inner surface of the refractory wall.

In testimony whereof, I have signed my name to this specification, in the presence of two subscribing witnesses.

CHARLES B. THWING.
